UNITED STATES PATENT OFFICE.

WILLIAM FRANCIS CUMNOR DEVLIN AND SIDNEY WALKER GRAHAM, OF OTTAWA,
ONTARIO, CANADA; SAID GRAHAM ASSIGNOR TO SAID DEVLIN.

SHUTTER-CONTROL MECHANISM FOR FOLDING CAMERAS.

Application filed December 17, 1921. Serial No. 523,112.

To all whom it may concern:

Be it known that we, WILLIAM FRANCIS CUMNOR DEVLIN and SIDNEY WALKER GRAHAM, both subjects of the King of Great Britain, and both residents of the city of Ottawa, in the Province of Ontario and Dominion of Canada, have invented certain new and useful Improvements in Shutter Control Mechanism for Folding Cameras, of which the following is a specification.

This invention relates to improvements in shutter control mechanism for folding cameras, and particularly to means of this character applicable to cameras of the folding or collapsible type, in which the shutter is controlled both for instantaneous and time exposures by an oscillatory lever which is usually operated once downwardly for an instantaneous exposure to open and shut the shutter, and for time exposure is operated once to open the shutter and once again to close it.

The objects of the invention are to provide economical and practical means of this kind which may be fitted to existing types of foldable cameras without change in the shutter control mechanism or without entailing alterations in the present construction thereof, and whereby double exposures (instantaneous or time) are guarded against.

With these and other objects in view, hereinafter more fully described in detail, the invention consists essentially in the improved and novel combination and arrangement of parts disclosed in the accompanying specifications and drawings in which:

Figure 1 is a perspective view of an embodiment of the invention.

Figure 2 is a side view thereof.

Figure 3 is a front elevation.

Figure 4 is a perspective view of the shutter control mechanism in locked position.

Figure 5 is a longitudinal section.

Figure 6 is a longitudinal section of the shutter control mechanism unlocked.

Figure 7 is a perspective detail of the primary latch detached.

Figure 8 is a similar detail of the secondary latch, detached.

Figure 9 is a perspective detailed view of the rocker plate and crank rod.

Figure 10 is a perspective view of the invention detached from a camera.

Figures 11 and 12 are details of the film winding mechanism.

Figure 13 is a sectional detail of the inner rocker plate with under arm depressing spring and operating rod.

Figure 14 is a longitudinal section of the winding mechanism.

In the drawings, like characters of reference indicate corresponding parts in all the figures.

Referring to the drawings:

A indicates a folding or collapsible camera of any well known standard type and construction, divided for the purposes of this specification into two parts or sections, B comprising the body or film winding part, and C, the foldable and collapsible parts. The means hereinafter described, as already mentioned, are designed to be applied to existing cameras without material alteration of the present shutter control lever, and which is herein shown and described as applied to a folding camera with negligible structural alterations and modifications, equally adapted to box or other types of camera.

D is the oscillatory lever designed in the type of camera herein selected to control the shutter mechanism, which is not a part of the present invention and is, therefore, not described in detail. The movement of the lever D in this type of camera once downwardly operates the shutter, opening and closing it for instantaneous exposures, while for time exposures the lever is operated twice downwardly. With the present invention, however, latch mechanism controlled by the film winding device is provided whereby the operation of the oscillatory lever D is prevented until the film winding mechanism has been operated to wind the film already used and to replace it by a new one, thus preventing two exposures on the same film.

This shutter control mechanism comprises a primary latch lever 10 pivoted on a pin 11 in a slotted plate 12 suitably mounted on the front 13 of the extending or collapsible portion 14 of the camera. This latch lever 10 is provided with spring-actuated means 15 arranged in a cut-out at the back of the slotted plate 12, adapted in normal operative position to move the latch outwardly to engage at its upper end with the lever D, thereby latching it against movement.

16 is the secondary spring-actuated latch lever formed in U-shape to embrace the plate

12 adjacent to the top and to fit into a suitable notch 17 in the sides thereof. 18 are resilient means for this secondary latch lever whereby, on the film winding mechanism being operated, this lever on being released moves upwardly out of the notch 17 at the same time as the primary latch 10 is moved to a retracted position between the sides of the plate 12, being retained in such position by the secondary latch lever until released by movement of the lever D.

The disengaging or releasing of the primary latch lever 10 is directly brought about by means of a rod 19 mounted on the front 15 of the camera at 20 below the lens with freedom to rotate, and having one end upwardly and outwardly extending to form a crank member 21 adapted to operatively engage the lower end of the primary latch lever 10, the 20 opposite end of the rod 19 being designed to form a crank 24.

The operation of the shutter control mechanism in so far as it has been described, is as follows: The film winding device having been operated, the crank 24 is in turn slidably engaged to move upwardly, causing the crank 21 through the lever or rod 19 to move in the opposite direction outwardly, bringing with it the lower end of the primary latch 10, the upper end of said latch being at the same time moved to a retracted position inwardly to release the secondary latch 16 and the lever D, whereby the latter is free to move downwardly until it contacts with the secondary latch 16 to move it back into released position in the notch 17, the primary latch 10 at the same time again engaging in locking position with the lever D.

40 The crank 24 is adapted to engage with a longitudinally extending rocker plate 25 mounted on the inside of the camera door 26 at 27 and 28 in notches to prevent lateral movement. This rocker plate 25 is provided 45 with a suitable link plate 29 at its inner end and slidably connected thereby and by means of the link 30 is adapted to slide therein with a rocker plate 31 pivotally mounted in the bottom of the film winding portion of the camera.

32 is a bearing plate on the rocker 31 adapted to engage the other end of the link 30. The link 30 extends across the hinge of the camera door and is designed and is 55 formed with a slot 33 to allow the crank 24 to pass the hinge without being raised or actuated. The rocker 31 is provided with a spring under arm 34 adapted to keep the rockers 31 and 25 depressed. 35 is the curved 60 inner end of the rocker 31 designed to engage with a rod 36, adapted at its other end to be engaged and moved by the film winding device 37 comprising a winding shaft 38, cam ring 39 extending around the shaft 38 and eccentrically mounted thereon at 40, and

70 spring held in normal position by the spring means 41. 42 is the winding member connected to the cam ring 39 whereby, on being wound anti-clockwise, the ring 39 will be moved eccentrically to move the rod 36. 75 43 is a suitable covering plate adapted to lie against the spring 41. 44 is the usual operating pressure bulb for the shutter control lever D.

75 From the foregoing, the complete operation of our invention, will be readily understood and appreciated and is as follows: The film roll having been secured in place on the winding device, the shutter lever D will be, for operative purposes, locked or 80 latched, in that it cannot move downwardly to open the shutter by reason of the fact that it is latched on the primary latch lever 10. To change the lever 10 from this position and to enable the shutter to be operated for 85 either an instantaneous or a time exposure, the film winding device is now turned in an anti-clockwise direction, when it will engage eccentrically with the rod 36, giving it a downward movement to bear on the rocker 90 plate 31 which, in turn, conveys the movement through the link 30 to the other rocker plate 25, having slidably, releasable connection with the crank 24. The movement thus conveyed causes the crank 24 to move upwardly which, in turn, through the rod or 95 lever 19, operates the crank 21 to operate the primary latch 10 connected thereto at the bottom by moving same outwardly and, by means of the pivot 11, inwardly at the 100 top, thereby releasing the contact of the latch 10 with the lever D, and allowing the same lever D to operate the shutter while at the same time releasing the secondary latch 105 lever 16 and allowing it to spring upwardly, as already described, until released by movement of the lever D. Simultaneously with the contact of the lever D in its downward movement with the secondary latch 16, the 110 primary latch 10 is released from its retracted position to again engage with the lever D in locked position.

115 It will be seen that a camera equipped with our attachment will be practically proof against double exposure on a rolled film. After an exposure it is necessary to give the winding roll a turn so that the exposure mechanism may be operated. In doing this, an operator's attention is directed to the fact that the winding is necessary. Therefore, he 120 naturally winds the film the proper amount as indicated on the back of the film through the back of the camera.

125 Our device operates as well for a time exposure as for an instantaneous exposure. When a time exposure is being made, the operating lever D on the first upper stroke does not come quite to its highest position, and therefore holds the latch 10 in its inward position as shown in Figure 6. The lever D 130

is operated in the ordinary manner either by hand or by bulb, and it is not necessary for the person using the camera to pay any attention to the locking device, and after the 5 time exposure, the latch automatically locks the lever in the same manner as for an instantaneous picture.

As many changes could be made in the above construction and many apparently 10 widely different embodiments of our invention within the scope of the claims, constructed without departing from the spirit or scope thereof, it is intended that all matter contained in the accompanying specification 15 and drawings shall be interpreted as illustrative and not in a limiting sense.

What we claim as our invention is:

1. A folding camera comprising a film containing part, a film winding device therein, a folding and an extending part, shutter control mechanism on the extending part, means for preventing operation of the shutter control mechanism until after the film winding device has been operated including 25 a longitudinally movable rod operated by the film winding device, a rocker operatively connected to the rod, a link connected to the rocker, a second rocker on the folding part having slidable engagement with the link, and means for operatively connecting the second rocker with the shutter control mechanism.

2. In a camera, film winding device, shutter control mechanism, a longitudinally 30 movable rod operated by the film winding device, a pivoted rocker operated by the rod, a second pivoted rocker, a link connecting the first-mentioned pivoted rocker with the second pivoted rocker, a crank member having engagement with the second rocker, and means operated by the crank for preventing operation of the shutter mechanism until after the film winding mechanism has been operated.

3. In a camera, a film winding device, shutter control mechanism, a longitudinally movable rod operated by the film winding device, a pivoted rocker operated by the rod, a second pivoted rocker, a link connecting the first-mentioned pivoted rocker with the second pivoted rocker, the said link having slidable engagement with the second rocker, a crank member having engagement with the second rocker, and means operated by 55 the crank for preventing operation of the shutter mechanism until after the film winding mechanism has been operated.

4. A folding camera comprising a film containing part, shutter mechanism, a folding part carrying the shutter mechanism adapted to collapse into the film containing part, a hinged door, a film winding device, means for preventing operation of the shutter mechanism until after the film winding device 60 has been operated comprising a latch device

having a releasing lever, an operating part on the door adapted to engage the releasing-lever, an operating part on the film containing part adapted when the folding part is folded to engage the release lever, and means 70 for operatively connecting the two operative parts, the said means comprising a link pivoted to one part having slidable and pivotal engagement with the other part.

5. A folding camera comprising a film 75 containing part, shutter mechanism, an extending part carrying the shutter mechanism adapted to collapse into the film containing part, a hinged door, a film winding device, and means for preventing operation of the 80 shutter mechanism until after the film winding device has been operated comprising a rocker on the film containing part operated by the film winding device, a rocker on the door operatively connected to the first-men- 85 tioned rocker and adapted to be moved thereby, and a latch device connected to the shutter mechanism having releasing means adapted to be engaged by the rocker on the door.

6. A folding camera comprising a film containing part, shutter mechanism, a folding part carrying the shutter mechanism adapted to collapse into the film containing part, a hinged door, a film winding device, 95 and means for preventing operation of the shutter mechanism until after the film winding device has been operated comprising a rocker on the film containing part operated by the film winding device, a rocker in the 100 door operatively connected to the first-men- tioned rocker and adapted to be moved thereby, and a latch device connected to the shutter control device having releasing means adapted to be engaged by the rocker on the door, and having sliding engagement therewith, being adapted to disengage therefrom when the folding part is folded and being adapted when in folded position to be 105 engaged by the rocker on the film containing part.

7. In a camera, shutter control mechanism having a depressible operating lever, a pivoted latch device adapted normally to prevent operation of the lever, a film winding device, means operated by the film winding device for moving the latch to retracted position, and a second latch device spring-actuated and adapted to retain the first-men- 115 tioned latch device in retracted position, the second latch device being adapted to be engaged by the shutter control lever during its movement, and moved to a position which will release the first-mentioned latch device.

8. In a camera, shutter control mechanism and a shutter control lever, a pivoted spring-actuated latch device normally preventing operation of the lever having a notch therein, means for moving the latch lever to retracted position, a secondary latch lever having 120

ing means to extend into the notch in the first latch lever, the said means when in the said notch permitting the first latch lever to spring to engaged position, the said secondary latch lever being adapted to be engaged and moved to disengaged position by the shutter control lever.

9. In a camera, shutter control mechanism including an operating lever, primary latch device adapted to engage and normally prevent operation of the lever, a secondary latch device adapted in engaged position to prevent operation of the primary latch device and being releasable by movement of the shutter control lever, a crank adapted to move the primary latch device to retracted position, film winding mechanism, and means for operatively connecting the film winding mechanism with the crank.

10. In a camera, shutter control mechanism including an operating lever, primary latch device adapted to engage and normally prevent operation of the lever, a secondary latch device adapted in engaged position to prevent operation of the primary latch device and being releasable by movement of the shutter control lever, a crank adapted to move the primary latch device to retracted position, film winding mechanism, and means for operatively connecting the film winding mechanism with the crank, the said means including a pivoted rocker having releasable engagement with the end of the crank.

11. In a camera, shutter control mechanism including an operating lever, primary latch device adapted to engage and normally prevent operation of the lever, a secondary latch device adapted in engaged position to prevent operation of the primary latch device and being releasable by movement of the shutter control lever, a crank adapted to move the primary latch device to retracted position, film winding mechanism, and means for operatively connecting the film winding mechanism with the crank, the said means including a pivoted rocker plate having releasable engagement with the end of the crank, a second rocker, and a link connecting the two rockers.

12. In a camera, shutter control mechanism including an operating lever, a primary latch device adapted to engage and normally prevent operation of the lever, a secondary latch device adapted in engaged position to prevent operation of the primary latch device and being releasable by movement of the shutter control lever, a crank adapted to move the primary latch device to retracted position, film winding mechanism, and means for operatively connecting the film winding mechanism with the crank, the said means including pivoted rocker plates having releasable engagement with the end of the crank, a second rocker, and a link

connecting the two rockers, one end of the link having sliding as well as pivotal engagement.

13. In a camera, a film winding device including a winding shaft, a cam ring extending about the winding shaft and mounted thereon with limited freedom of movement to and from the axis of the shaft being spring-held in normal position, a winding member connected to the ring adapted when turned in one direction to cause the ring to move eccentrically, a rod adapted to be engaged and moved by a portion of the ring when moved eccentrically, and shutter control mechanism controlled from the rod. 70 75 80

14. A folding camera comprising a film containing part, a film winding device therein, a folding part, shutter control mechanism on the folding part, means for preventing operation of the shutter control mechanism 85 until after the film winding device has been operated including a longitudinally movable rod operated by the film winding device, a rocker operatively connected to the rod, a link connected to the rocker, a second rocker on the folding part having slidable engagement with the link, and means for operatively connecting either the first or second rocker with the shutter control mechanism.

15. In a camera, film winding device, 95 shutter control mechanism, a longitudinally movable rod operated by the film winding device, a pivoted rocker operated by the rod, a second pivoted rocker, a link connecting the first-mentioned pivoted rocker 100 with the second pivoted rocker, a crank member having engagement with either the first-mentioned rocker or the second rocker, and means operated by the crank for preventing operating of the shutter mechanism until 105 after the film winding mechanism has been operated.

16. In a camera, a film winding device, shutter control mechanism, a longitudinally movable rod operated by the film winding 110 device, a pivoted rocker operated by the rod, a second pivoted rocker, a link connecting the first-mentioned pivoted rocker with the second pivoted rocker, the said link having slidable engagement with the second rocker, 115 a crank member having engagement with the first-mentioned rocker or the second rocker, and means operated by the crank for preventing operation of the shutter mechanism until after the film winding mechanism has 120 been operated.

17. In a camera, shutter control mechanism including an operating lever, primary latch device adapted to engage and normally prevent operation of the lever, a secondary latch device adapted in engaged position to prevent operation of the primary latch device and being releasable by movement of the shutter control lever, a crank adapted to 125 move the primary latch device to retracted 130 135

position, film winding mechanism, and means for operatively connecting the film winding mechanism with the crank, the said means including a pivoted rocker plate having slideable engagement with the end of the crank.

18. In a camera, shutter control mechanism including an operating lever, primary latch device adapted to engage and normally prevent operation of the lever, a secondary latch device adapted in engaged position to prevent operation of the primary latch device and being releasable by movement of the shutter control lever, a crank adapted to move the primary latch device to retracted position, film winding mechanism, and means for operatively connecting the film winding mechanism with the crank, the said means including a rocker plate having slideable engagement with the end of the crank, a second rocker, and a link connecting the two rockers, spring means beneath one of said rockers whereby both rockers are kept depressed.

19. In a camera, shutter control mechanism including an operating lever, prim-

ary latch device adapted to engage and normally prevent operation of the lever, a secondary latch device adapted in engaged position to prevent operation of the primary latch device and being releasable by movement of the shutter control lever, a crank adapted to move the primary latch device to retracted position, film winding mechanism, and means for operatively connecting the film winding mechanism with the crank, the said means including a rocker plate having slideable engagement with the end of the crank, a second rocker, and a link connecting the two rockers, spring means beneath one of said rockers whereby both rockers are kept depressed.

In witness whereof we have hereunto set our hands in the presence of a witness.

WILLIAM FRANCIS CUMNOR DEVLIN.
SIDNEY WALKER GRAHAM.
